(57) **CLAIM**

The ornamental design for a blower unit, as shown and described.

DESCRIPTION

FIG. 1 is a front and right side perspective view of a blower unit, showing our new design;

FIG. 2 is a rear and left side perspective view thereof;

FIG. 3 is a front elevational view thereof;

FIG. 4 is a rear elevational view thereof;

FIG. 5 is a right side elevational view thereof;

FIG. 6 is a left side elevational view thereof; and,

FIG. 7 is a top plan view thereof.

The broken lines shown in the drawings are for the purpose of illustrating portions of the blower unit and form no part of the claimed design.
